(57) **CLAIM**

The ornamental design for an emergency training aid device, as shown.

DESCRIPTION

FIG. 1 is a perspective view of an emergency training aid device showing my new design;

FIG. 2 is a front view thereof with the door being shown in broken line for clarity of illustration;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken line showing of doorway is included for the purpose of illustration and forms no part of the claimed design.
